UNITED STATES PATENT OFFICE

153,095

DESIGN FOR A COMBINATION
KITCHEN UNIT

Robert C. Armbruster, Louisville, Ky., assignor to Reynolds Metals Company, Richmond, Va., a corporation of Delaware

Application January 18, 1946, Serial No. 125,683

Term of patent 14 years

(Cl. D33—19)

To all whom it may concern:

Be it known that I, Robert C. Armbruster, a citizen of the United States, residing in Louisville, in the county of Jefferson and State of Kentucky, have invented a new, original, and ornamental Design for Combination Kitchen Unit, of which the following is a specification, reference being had to the accompanying drawings, forming part thereof.

Fig. 1 is a front perspective view of a combination kitchen unit, showing my new design, and

Fig. 2 is a side elevational view thereof.

I claim:

The ornamental design for a combination kitchen unit, as shown.

ROBERT C. ARMBRUSTER.
